Aug. 21, 1934.

W. R. MOBLEY

1,971,015

AIR PROPELLING DEVICE

Filed Jan. 26, 1931

3 Sheets-Sheet 1

Aug. 21, 1934.

W. R. MOBLEY

1,971,015

AIR PROPELLING DEVICE,

Filed Jan. 26, 1931

3 Sheets-Sheet 2

INVENTOR
William Robert Mobley

Aug. 21, 1934.

W. R. MOBLEY

1,971,015

AIR PROPELLING DEVICE

Filed Jan. 26, 1931

3 Sheets-Sheet 3

INVENTOR.
William Robert Mobley

Patented Aug. 21, 1934

1,971,015

side of the blades 4 while a vacuum is created at the rear of the blades as at 20. The blades 14 are compelled to rotate in opposite directions by the action of a pressure on one side 5 and a vacuum on the other side, and as part of the blades 14 operate within the opening 3 they collect air therefrom and force it against the inner surface of the outer casing which air is discharged through the opening 6 by the 10 inclined surfaces 21 operating behind the flange 2.

It will be observed that in the foregoing specification and drawings I have provided an air propelling device of such character that it 15 utilizes its entire surface area to produce vacuums and pressures from an air stream passing through itself for the purpose of forward propulsion.

Having now particularly described and ascertained the nature of my invention and the manner in which same may be performed what I claim as new and desire to secure by United States Letters Patent is:

In an air propulsion device the combination of a peripheral casing rotary around an axis, a flange at the front of said device and extended inward from said casing toward the axis and having a central opening, a disc opposite to said opening, and arranged at the rear of said device, said disc closing the central part of the rear of the device and having around it an air escape opening near the casing, and blades having surfaces parallel with the axis extending from said casing inward and towards points which are at a distance from the axis of the device.

WILLIAM ROBERT MOBLEY.

- (54) 510, 511, 512
1. A peripheral casing 10 having a central opening 12, a flange 14 at the front of said device and extended inward from said casing toward the axis and having a central opening, a disc 16 opposite to said opening, and arranged at the rear of said device, said disc closing the central part of the rear of the device and having around it an air escape opening 18 near the casing, and blades 20 having surfaces parallel with the axis 22 extending from said casing inward and towards points which are at a distance from the axis of the device.
2. The combination as in claim 1, and further including a central opening 24 in the disc 16.
3. The combination as in claim 1, and further including a central opening 24 in the disc 16, and a flange 26 at the rear of the device.
4. The combination as in claim 1, and further including a central opening 24 in the disc 16, and a flange 26 at the rear of the device, and a central opening 28 in the disc 16.
5. The combination as in claim 1, and further including a central opening 24 in the disc 16, and a flange 26 at the rear of the device, and a central opening 28 in the disc 16, and a central opening 30 in the flange 26.
6. The combination as in claim 1, and further including a central opening 24 in the disc 16, and a flange 26 at the rear of the device, and a central opening 28 in the disc 16, and a central opening 30 in the flange 26, and a central opening 32 in the peripheral casing 10.
7. The combination as in claim 1, and further including a central opening 24 in the disc 16, and a flange 26 at the rear of the device, and a central opening 28 in the disc 16, and a central opening 30 in the flange 26, and a central opening 32 in the peripheral casing 10, and a central opening 34 in the peripheral casing 10.
8. The combination as in claim 1, and further including a central opening 24 in the disc 16, and a flange 26 at the rear of the device, and a central opening 28 in the disc 16, and a central opening 30 in the flange 26, and a central opening 32 in the peripheral casing 10, and a central opening 34 in the peripheral casing 10, and a central opening 36 in the peripheral casing 10.
9. The combination as in claim 1, and further including a central opening 24 in the disc 16, and a flange 26 at the rear of the device, and a central opening 28 in the disc 16, and a central opening 30 in the flange 26, and a central opening 32 in the peripheral casing 10, and a central opening 34 in the peripheral casing 10, and a central opening 36 in the peripheral casing 10, and a central opening 38 in the peripheral casing 10.
10. The combination as in claim 1, and further including a central opening 24 in the disc 16, and a flange 26 at the rear of the device, and a central opening 28 in the disc 16, and a central opening 30 in the flange 26, and a central opening 32 in the peripheral casing 10, and a central opening 34 in the peripheral casing 10, and a central opening 36 in the peripheral casing 10, and a central opening 38 in the peripheral casing 10, and a central opening 40 in the peripheral casing 10.
11. The combination as in claim 1, and further including a central opening 24 in the disc 16, and a flange 26 at the rear of the device, and a central opening 28 in the disc 16, and a central opening 30 in the flange 26, and a central opening 32 in the peripheral casing 10, and a central opening 34 in the peripheral casing 10, and a central opening 36 in the peripheral casing 10, and a central opening 38 in the peripheral casing 10, and a central opening 40 in the peripheral casing 10, and a central opening 42 in the peripheral casing 10.
12. The combination as in claim 1, and further including a central opening 24 in the disc 16, and a flange 26 at the rear of the device, and a central opening 28 in the disc 16, and a central opening 30 in the flange 26, and a central opening 32 in the peripheral casing 10, and a central opening 34 in the peripheral casing 10, and a central opening 36 in the peripheral casing 10, and a central opening 38 in the peripheral casing 10, and a central opening 40 in the peripheral casing 10, and a central opening 42 in the peripheral casing 10, and a central opening 44 in the peripheral casing 10.
13. The combination as in claim 1, and further including a central opening 24 in the disc 16, and a flange 26 at the rear of the device, and a central opening 28 in the disc 16, and a central opening 30 in the flange 26, and a central opening 32 in the peripheral casing 10, and a central opening 34 in the peripheral casing 10, and a central opening 36 in the peripheral casing 10, and a central opening 38 in the peripheral casing 10, and a central opening 40 in the peripheral casing 10, and a central opening 42 in the peripheral casing 10, and a central opening 44 in the peripheral casing 10, and a central opening 46 in the peripheral casing 10.
14. The combination as in claim 1, and further including a central opening 24 in the disc 16, and a flange 26 at the rear of the device, and a central opening 28 in the disc 16, and a central opening 30 in the flange 26, and a central opening 32 in the peripheral casing 10, and a central opening 34 in the peripheral casing 10, and a central opening 36 in the peripheral casing 10, and a central opening 38 in the peripheral casing 10, and a central opening 40 in the peripheral casing 10, and a central opening 42 in the peripheral casing 10, and a central opening 44 in the peripheral casing 10, and a central opening 46 in the peripheral casing 10, and a central opening 48 in the peripheral casing 10.
15. The combination as in claim 1, and further including a central opening 24 in the disc 16, and a flange 26 at the rear of the device, and a central opening 28 in the disc 16, and a central opening 30 in the flange 26, and a central opening 32 in the peripheral casing 10, and a central opening 34 in the peripheral casing 10, and a central opening 36 in the peripheral casing 10, and a central opening 38 in the peripheral casing 10, and a central opening 40 in the peripheral casing 10, and a central opening 42 in the peripheral casing 10, and a central opening 44 in the peripheral casing 10, and a central opening 46 in the peripheral casing 10, and a central opening 48 in the peripheral casing 10, and a central opening 50 in the peripheral casing 10.
